UNITED STATES PATENT OFFICE.

WINFRED T. POWELL, OF ROCHESTER, NEW YORK, ASSIGNOR TO THE STROMBERG-CARLSON TELEPHONE MANUFACTURING COMPANY, OF ROCHESTER, NEW YORK, A CORPORATION OF NEW YORK.

AUTOMATIC TELEPHONE SYSTEM.

Application filed January 16, 1922. Serial No. 529,542.

This invention relates to telephone systems and more particularly to telephone systems employing automatic switches in completing telephone connections.

5 In former telephone systems the directly operated magnets of the numerical switches have been controlled at contacts of impulse relays operated over the two sides of the line in series, with the result that on 10 long telephone lines the impulse relay is only weakly operated so that a complete impulse is not transmitted to the operating magnet. This resulted in improper operation of the 15 numerical switches and the consequent error in connections.

The purpose of the present invention is to provide an arrangement in which the directly operated magnets of the numerical switches will be positively operated irrespective of the length of telephone lines over 20 which they are controlled.

The main feature of the present invention is the use of inductive means for repeating 25 impulses to the directly operated magnets of non-numerical switches. Other features of the invention include the detailed circuits by which such operation is achieved, all of which will be brought out in the detailed description and the appended claims.

30 In the drawings Fig. 1 represents a telephone system including the present invention. The portion of the drawing at the left of the dotted line represents the calling telephone line and the circuits of a selector switch; at the right of the dotted line there is diagrammatically represented the 35 circuits of a connector switch and a called telephone line. The connector in Fig. 1 is of that type known in the art as a side-switchless connector.

Fig. 2 represents a modified form of the invention applied to a connector switch circuit of the type known in the art as, a connector switch with side-switch.

45 The mechanical structure of the selector switch herein referred to may be of the type disclosed in the patent to Keith, Erickson and Erickson #815,821 issued March 13, 1906, while the mechanical structure of the 50 connector switch may be similar to the patent to Keith, Erickson and Erickson #815,176, patented March 13, 1906. It will

be understood, of course, that if this type of connector is employed in the circuits of Fig. 1 the side switch may be omitted.

It is believed that the invention will best be understood by describing the method of establishing a telephone connection from a subscriber at the sub-station, indicated at A to a subscriber whose substation is indicated at B.

When the subscriber at A removes his receiver from its switch hook, a non-numerical switch of any well known type operates to extend the calling line to an idle trunk 65 which leads to an idle selector switch. Let it be assumed that the non-numerical switch seizes the trunk, whose conductors 5 and 6 lead to the selector switch of Fig. 1. As soon as this switch is seized, its impulse 70 relay 7 will be energized from grounded battery, through its right hand winding, uppermost back contact and armature of cut-through relay 8, over the upper side of the 75 established connection, including conductor 5, through the substation circuits at A, over the lower side of this connection including conductor 6, inner armature and back contact of relay 8, left hand winding of relay 7 to ground. The relay 7 is energized in 80 this circuit and at its armature and front contact completes a circuit for operating the slow releasing relay 9 and completes a circuit in multiple therewith for the relay 10, which circuit is traced from grounded 85 battery, left hand winding of the relay 10, front contact and armature of relay 7, lowermost back contact and armature of relay 8 to ground. The relay 10 is energized in 90 this circuit, but its right hand winding, which is inductively connected with the left hand winding, is short circuited at its armature and back contact. On the energization of relay 10, however, its armature is attracted so that when it deenergizes, a current is induced in the right hand winding 95 of this relay which operates the relay 11, as will be described. At the left hand armature and contact of relay 9, the circuit for the release magnet 12 is opened, thereby 100 preventing the release of the selector switch at this time. At the right hand armature and front contact of relay 9, ground is applied to conductor 13 which serves to pre-

vent, temporarily, the release of the non-numerical switch as will be understood from this description.

In response to the series of impulses corresponding to the first digit of the wanted number, relay 7 vibrates its armature once for each impulse. At the retraction of the armature of relay 7, the energizing circuit of the relay 10 will be interrupted causing a current to be induced in the closed circuit including the right hand winding of relay 10 and the winding of relay 11. This will operate relay 11 and thereby complete an operating circuit for the primary motor magnet 14, from grounded battery, winding of this magnet, slow releasing change-over relay 15, armature and front contact of relay 11, lowermost back contact and armature of relay 8 to ground. At each completion of this circuit of the primary motor magnet, it advances the brushes 16, 17 and 18 of the selector in their primary direction to select a group of trunks through which the called line may be reached. At the termination of this series of impulses, the impulse relay 7 maintains its armature attracted for a relatively long interval, thereby permitting the change-over relay 15 to deenergize. The relay 19 has been maintained energized in a circuit completed from grounded battery winding of this relay, off normal contacts 20, armature and continuity spring of relay 15, conductor 13, armature and front contact of relay 9 to ground. Thus, when the slow releasing change-over relay 15 deenergizes, a circuit is closed from grounded battery, winding of the secondary magnet 21, inner front contact and armature of relay 19, back contact and continuity spring of relay 15, armature and front contact of relay 9 to ground. Under the control of this circuit the secondary motor magnet 21, advances the brushes 16, 17 and 18 of the selector switch into engagement with the first trunk of the selected group. Let it be assumed that this trunk is busy when it is thus tested by the test brush 18, which busy condition will be indicated by the presence of ground potential on its test terminal, applied at the left hand front contact and armature of the relay corresponding to 22, associated with the busy trunk. When the test brush 18 engages this busy trunk a circuit will be closed from ground, the test terminal of the busy trunk, test brush 18, armature and back contact of relay 8, conductor 23, armature and back contact of the secondary motor magnet 21, of normal contacts 20, winding of relay 19 to grounded battery.

At this time a circuit is closed for the relay 8 which is ineffective to operate this relay at this time. This circuit extends from grounded battery, winding of relay 19, off normal contact 20, back contact and armature of magnet 21, conductor 23, winding of

relay 8, conductor 13, armature and front contact of relay 9 to ground. It will be noted that this circuit is ineffective to operate relay 8 while the test brush 18 is encountering busy test terminals which are characterized by the presence of ground potential. With the relay 19, operated over the circuit last described, the energizing circuit for the magnet 21 will be closed from grounded battery, winding of this magnet, inner contact and armature of relay 19, back contact and continuity spring of relay 15, armature and front contact of relay 9 to ground. The secondary motor magnet 21 is operated in this circuit and advances the selector switch brushes into engagement with the next trunk of the selector group. When the secondary motor magnet 21 operates it opens the circuit of relay 19 causing it to deenergize. If, however, the trunk which is now being tested by the test brush 18 is busy, the relay 19 will again be operated to cause another operation of the secondary motor magnet 21 and the consequent advancement of the selector switch brushes. It will thus be seen that the relay 19 on energization closes an operating circuit for the motor magnet 21, and this magnet when it operates opens the energizing circuit of the relay 19 to effect its deenergization and this relay will only operate again, if the test brush 18 is still in engagement with the test terminal of a busy trunk.

Let it be assumed that the first idle trunk tested by the test brush 18 is that represented in Fig. 1, the test terminal 24 of which is characterized by the absence of potential thereon, due to the fact that its associated relay 22 is not operated. The relay 8 will no longer be short circuited but will be operated in the circuit previously described. At the upper armatures and back contacts of relay 8, the impulse relay 7 of the selector is removed from the control of the calling line and the conductors 5 and 6 of the first selector trunk are extended to the brushes 16 and 17 of the selector switch. The impulse relay 25 of the connector switch will thereupon be energized in the circuit extending from grounded battery, left hand winding of this relay back contact and continuity spring of relay 26 over the upper side of the connection, thus far established through the sub-station A, over the lower side of the connection including conductor 6 and selector brush 17, continuity spring and back contact of relay 26, right hand winding of 25 to ground. Relay 25 is energized in this circuit and at its front contact and armature completes an energizing circuit for the slow releasing relay 22. This last mentioned relay attracts its armatures and at its left hand armature and front contact applies ground potential to the test terminal 24 of the last selected

trunk, which serves to render this trunk busy. A locking circuit for the relay 8 is also completed at the armature and front contact of relay 22, through the test terminal 24, test brush 18, innermost lower armature and front contact of relay 8, winding of this relay, conductor 23, armature and contact of magnet 21, off normal contacts 20, winding of relay 19 to grounded battery. Relays 19 and 8 are so designed that the relay 8 will be energized in this circuit, but the relay 19 will remain inactive.

When relay 25 attracted its armature, it closed an operating circuit for the relay 27 in multiple with that of the relay 22. This circuit is traceable from ground, armature and front contact of relay 25, left hand winding of relay 27 to grounded battery. The relay 27 is energized in this circuit and induces a current in its right hand winding, but this current is ineffective to operate the relay 28 because the right hand winding of relay 27 is short circuited at its armature and back contact. When, however, the relay 27 is energized the short circuit is removed from the right hand winding of relay 27 and this winding will be effective to operate the relay 28 for purposes to be further described.

The apparatus and circuits of the connector switch are now in condition to receive the series of impulses corresponding to the tens digit of the wanted number. The subscriber at A now operates his dial sender to transmit the tens series of impulses and in response to each of these impulses, the impulse relay 25 retracts its armature. This, however, will be ineffective to cause the operation of the release magnet 29 because its circuit is now open at the outer armature and back contact of relay 22. When the relay 25 thus retracts its armature it opens the energizing circuit of the relay 27 and, as has been described, this relay deenergizes and induces a current in its right hand winding to cause the energization of relay 28. This relay closes a circuit from ground, armature and front contact of relay 28, off normal contact springs 30 and 31, winding of the change-over relay 33, winding of the primary motor magnet 34 to grounded battery. The slow releasing relay 33 is energized in this circuit and at its armature and back contact holds open the operating circuit of the secondary motor magnet 35 of the connector switch. The primary magnet 34, therefore, is operated in this circuit and advances the brushes 36, 37 and 38 of the connector switch one step in its primary movement. This is effective to open the off-normal contacts 30 and 31 but contact springs 30 and 32 are closed before this takes place, since the contact springs 30, 31 and 32 are of the make-before-break arrangement. In response to the re-

mainder of the tens series of impulses, the relay 28 will be operated in the manner already described, to close intermittently an operating circuit for the primary motor magnet 34 from grounded battery, winding 70 of this magnet, winding, front contact and armature of the change-over relay 33, off normal contacts 30 and 32, front contact and armature of relay 28 to ground. The primary motor magnet will continue to operate in this circuit until the connector switch brushes are placed in operative position to the group of lines including the wanted telephone line. At the close of this series of impulses, the impulse relay 25 will maintain its armature attracted for a relatively long interval so that no impulse will be inductively transmitted to the relay 28, consequently the operating circuit of the relay 33 will be open for a relatively long period causing this relay to deenergize. The connector is now in condition to receive the series of impulses corresponding to the units digit of the wanted number.

The subscriber at A now operates his dial sender to send this series of impulses and in response to each impulse the operating circuit of the relay 27 is opened and this relay induces an impulse of current in the winding of relay 28. This last mentioned relay, thereupon, attracts its armature to close a circuit from ground through contacts 30 and 32, armature and back contact of the change-over relay 33, inner back contact and armature of relay 39, armature 40, of relay 41, winding of the secondary motor magnet 35 to grounded battery. This secondary motor magnet is actuated in this circuit and advances the set of brushes one step in their secondary direction.

On the first operation of the relay 28 and in response to the first units impulse the slow releasing relay 42 will be energized in multiple with the secondary magnet 35 and this relay when operated, closes a locking circuit for itself, through its left hand front contact and armature. In response to each of the units impulses the secondary motor magnet advances the connector switch brushes until at the close of this series of impulses the brushes 36, 37 and 38 of the connector will be in operative engagement with the terminals of the wanted line leading to substation B. At this time the operating circuit of relay 42 will be maintained open for a relatively long period, so that this relay will deenergize.

Let it first be assumed that the wanted line is idle at this time, whereupon a circuit is closed from grounded battery, winding of the cut-off relay 43 of this line, its test terminal 50, test brush 38, right hand armature and back contact of relay 42, upper winding of relay 41, back contact and armature of relay 39, conductor 44, front contact and

4

armature of relay 22 to ground. Relay 41 is operated in this circuit and closes a locking circuit for itself from grounded battery, through its lower winding, innermost lower front contact and armature, conductor 45, inner front contact and armature of relay 22 to ground. Relay 41 when operated also closes its upper front contacts and armatures, thereby closing a ringing circuit extending from the ringing generator (not shown) conductor 46, inner back contact and armature of the trip relay 47, inner upper front contact and armature of relay 41, connector brush 37, through the substation circuits, over the upper side of the called line, connector brush 36, uppermost armature and front contact of relay 41, uppermost armature and back contact of relay 47, upper winding of the trip relay 47 to grounded battery. Over this circuit ringing current is applied to the called line until the subscriber at substation B removes his receiver from its switch hook, at which time the relay 47 will receive sufficient current to be energized and will attract its armatures. At the upper armatures of relay 47 a talking connection is completed and at the inner lower armature and contact of relay 47, a locking circuit is completed for this relay through its lower winding, conductor 45, front contact and armature of relay 22 to ground. At this time a circuit is closed for relay 26 extending from grounded battery, left hand winding of this relay, over the upper side of the connection to the called line, and its substation circuits in series, over the lower side of the established connection, right hand winding of relay 26, inner lower front contact and armature of relay 47, conductor 45, inner front contact and armature of relay 22 to ground. The relay 26 attracts its armatures and at its inner right hand armature and back contact opens a second break point in the circuit of the release magnet 29 for a purpose which will be later described. At the left hand armatures and continuity springs of relay 26, battery is reversed in the calling side of the connection to operate a call registering device or for other purposes incident to the operation of an automatic exchange. At the outer right hand armature and front contact of relay 26 it extends conductor 45 through the lowermost front contact and armature of relay 47, contact 49 and armature of relay 41 to ground, so that the holding circuit for relays 26, 41 and 47 is maintained independent of the control of the calling subscriber.

Talking battery is supplied to the calling party through the windings of relay 25, while talking battery for the called subscriber is applied through the windings of relay 26.

Let it be assumed that the wanted line is busy at the time it is tested which condi-

tion will be indicated by the presence of ground potential on its test terminal 50 applied through a test brush similar to 38 of the connector switch which has previously seized this line through the front contact 70 and armature similar to 51 of a relay similar to 41 to ground at the connector switch which has already seized this line. Therefore at the time of the test, a circuit will be completed from this ground, test terminal 75 50, test brush 38, armature and continuity spring of relay 42, lowermost back contact and armature of relay 41, winding of test relay 39 to grounded battery. This last mentioned relay is energized in this circuit and 80 when relay 42 deenergizes it closes a locking circuit for relay 39 from grounded battery, its winding, lowermost armature and back contact of relay 41, continuity spring and back contact of relay 42, right hand 85 front contact and armature of relay 39, conductor 44, left hand front contact and armature of relay 22 to ground.

At the inner armature and back contact of relay 39 the operating circuit of the secondary motor magnet 35 is interrupted to prevent its further operation in the event that the subscriber at A should operate his dial sender to send additional impulses. At the outer armature and front contact of relay 39 a source of busy tone current B Z is extended over conductor 52 to the calling line to indicate to the subscriber at A that the wanted line is not available.

At the close of the conversation when the subscriber at A replaces his receiver on his switch hook, the energizing circuit for the relay 25 will be opened and this relay will deenergize. Shortly after this the slow releasing relay 22 which is controlled by the relay 25 deenergizes. At the left hand armature and front contact of relay 22, the holding circuit for the relay 8 of the selector is opened and in the event that the wanted line was busy when tested, the locking circuit of test relay 39 is also opened at the left hand armature and front contact of relay 22. Under this condition the circuit of the release magnet 29 of the connector switch, is closed at the outer armature and back contact of relay 22. The relay 8 thereupon deenergizes and a circuit is now closed for the release magnet 12 extending from grounded battery, winding of this magnet, off normal contacts 54, back contacts and armatures of relays 9, 7 and 8 to ground. The release magnet 12 is energized in this circuit and effects the release of the selector switch in the well known manner.

It will be noted at this time that the releasing of the connector switch is not effected because the circuit of this release magnet 29 is held open at the inner armature and back contact of relay 26. The connector switch under consideration is so ar-

ranged that both the calling and called subscribers must have terminated the conversation by replacing their receivers on their respective switch hooks before it is released. When the called party terminates the conversation the relay 26 deenergizes and if the calling party has terminated the connection relay 22 will also be deenergized so that an operating circuit for the release magnet 29 of the connector switch will be closed from grounded battery, winding of this magnet, off normal contacts 55, back contact and armature of relay 26, back contacts and armatures of relays 22 and 25 to ground. Magnet 29 is energized in this circuit to effect the release of the connector switch in the well known manner.

In the modified form of the invention shown in Fig. 2, the improved impulsive arrangement is shown in connection with a connector provided with a side switch. For purposes of this description, it may be assumed that the calling line A has been extended through the non-numerical switch 25 and the selector switch of Fig. 1 and that the selector switch is stopped with its brushes 16, 17 and 18 in engagement with the terminals 56, 57 and 94 of the trunk circuit individual to the connector switch of 30 Fig. 2 through which the wanted line and its substation C may be reached.

Since the connection has been established through the calling line and the selector switch brushes 16 and 17 in engagement with the terminals 56 and 57, the impulse relay 58 will be energized over the two sides of the extended connection in series, through both windings of this relay to ground and grounded battery respectively. The impulse relay 58 is energized in this circuit and closes an operating circuit for the relay 59 at its front contact and armature. The relay 59 attracts its armature and at its front contact extends ground potential to the test terminal 94 which serves to guard this trunk against intrusion and also completes a holding circuit for the relay 8 in the manner already described. At the back contact and armature of relay 59 a break point is opened in the circuit of the release magnet 60 to prevent the release of the connector switch. At the time when the relay 58 attracts its armature, it also closes an energizing circuit for the relay 61 in multiple with that of the relay 59. This circuit is completed from ground, armature and front contact of relay 58, upper winding of relay 61 to grounded battery. The lower winding of the relay 61 is inductively associated with the upper winding of this relay and on each energization and deenergization of the upper winding an impulse of current is induced in the lower winding of relay 61. It will be noted that at the time that relay 61 is energized there will be a short circuit

about relay 62, including the armature and back contact of relay 61. When relay 61 is energized it attracts its armature and opens this short circuit so that when the relay 61 deenergizes the impulse induced in the lower winding of this relay will actuate the relay 62.

The circuits of the connector switch are now in condition to receive the tens series of impulses and the subscriber at A operates his dial sender to send a series of impulses and causes the relay 58 to vibrate its armature in the well known manner. On each interruption it opens the circuit including the upper winding of the relay 61. This causes an induced impulse to actuate the relay 62 and attract its armature. This closes an operating circuit for the primary motor magnet 63 from grounded battery, winding of this magnet, side switch wiper 65 in its first position, front contact and armature of relay 62 to ground. In response to each of these impulses the motor magnet 63 advances the brushes 67, 68 and 69 of the connector switch in their primary direction to select the group of lines including the wanted telephone line.

It will be noted that the slow releasing relay 70 is energized in multiple with the primary motor magnet 63 at this time and completes an energizing circuit for the escape magnet 71 of the side switch, which circuit is closed from grounded battery, resistance winding of this magnet, continuity spring and armature of relay 70 to ground. The structure of the side switch is well known and need not be described here. It is sufficient to say that at the close of the tens series of impulses the relay 70 deenergizes and opens the circuit of the escape magnet 71 which releases to move the side switch wipers into their second position.

The circuits are now in condition to receive the directive impulses corresponding to the units digit of the wanted number. The subscriber at substation A operates his impulse sender to transmit a series of impulses corresponding to the units digit of the wanted number. In response to each of these impulses the relay 58 will retract its armature and this will be effective to induce an impulse to actuate the relay 62 in the manner already outlined. As soon as the relay 62 actuates its armature it closes a circuit for energizing the relay 70 and this in turn effects the energization of the escape magnet 71. At this time a circuit is closed from ground, armature and front contact of relay 62, side switch wiper 65 in its second position, back contact and armature of relay 72, winding of the secondary motor magnet 64 to grounded battery.

In response to each of these impulses, on each attraction of the armature of relay 62, the secondary motor magnet 64 will advance

the brushes 67, 68 and 69 of the connector switch until these brushes are in operative relation with the terminals 92, 73 and 74 of the wanted line. At the close of this series 5 of impulses when the connector switch brushes have thus been positioned, the armature of relay 62 will be retracted for a relatively long period which will effect the de-energization of the slow releasing relay 70. 10 This last mentioned relay will cause the deenergization of the escape magnet 71 which in turn moves the side switch wipers into their third position provided the called line is idle. It will subsequently be described what takes place if this line is busy.

With the side switch wipers in their third position the escape magnet is energized in a circuit extending through side switch wiper 91 and back contact of release magnet 60 to 20 ground. Ringing current is also supplied to the called line from the ringing machine generally designated 75, through resistance lamp 76, trip relay 77, side switch wiper 78, brush 68, terminal 73, through the called 25 substation circuits, over the upper side of the called line, terminal 92, connector brush 67, side switch wiper 79 in its third position to ground. Ringing current is applied over this circuit until the called subscriber responds by removing his receiver from its 30 switch hook at which time the trip relay 77 will receive sufficient current to be energized and will attract its armature. This will short circuit the escape magnet 71 35 which will deenergize and move the side switch wipers to their fourth or talking position.

Talking current is supplied to the calling line through the windings of impulse relay 40 58 while talking battery is supplied to the called party through the windings of impedance coil 89.

Let it be assumed that the called line is 45 busy when the test brush 69 engages the test terminal 74. At this time the escape magnet 71 will be energized and the side switch wipers will be in their second position. However, when slow releasing relay 70 deenergizes the escape magnet will be 50 held operated in a circuit now traceable from grounded battery, its winding, continuity spring and back contact of relay 70, winding of test relay 72, continuity spring and back contact of this relay, conductor 82, 55 side switch wiper 83 in its second position, test brush 69, test terminal 74 and through the multiple terminal thereof, through the brush similar to 69 and a side switch wiper similar to 83 in its third and fourth positions to ground at the connector switch which has already seized the called line. The test relay 72 is energized in this circuit 60 and closes a locking circuit for itself in series with the escape magnet 71, through 65 continuity spring and back contact of relay

70, winding, continuity spring and armature of relay 72 and off normal contacts 81 to ground. With the test relay 72 operated a source of busy tone current is transmitted from source B Z over conductor 84 armature and front contact of relay 72 to the calling line.

When the calling subscriber at A terminates the connection by replacing his receiver on its switch hook the energizing circuit of the relay 58 will be interrupted causing this relay to deenergize and retract its armature. This will open the energizing circuit of the slow releasing relay 59 and shortly afterwards this relay also retracts its armature. At its armature and front contact it removes the holding ground which has been applied to the test terminal during the conversation, and this permits the release of the selector switch of Fig. 1 in the manner already described. At the back contact and armature of relay 59 an operating circuit is closed for the release magnet from ground, through off normal contacts 86, winding of the release magnet 60 to grounded battery. The release magnet is operated in this circuit and effects the release of the connector switch in the well known manner.

What is claimed is:—

1. In an automatic telephone system, an incoming circuit, a plurality of outgoing circuits, a numerical switch individual to said incoming circuit for connecting said incoming circuit to any of said outgoing circuits, a motor magnet for said numerical switch, means for transmitting impulses over said incoming circuit, an impulse relay normally connected to said incoming circuit and responsive to impulses from said impulse transmitting means, a transformer relay energized in response to each impulse transmitted to said impulse relay, and means inductively connected to said transformer relay and responsive to impulses for effecting the operation of the motor magnet of said numerical switch said inductively connected means being controlled by contacts on said transformer relay.

2. In a telephone system, an incoming circuit, a plurality of outgoing circuits, an automatic switch individual to said incoming circuit for connecting said incoming circuit to any of said outgoing circuits, a motor magnet for operating said automatic switch, an impulse transmitting device for transmitting impulses over said incoming circuit, an impulse relay normally connected to said incoming circuit and responsive to impulses transmitted from said impulse transmitting device, a transformer relay controlled by said impulse relay, a third relay normally short-circuited by and inductively connected to said transformer relay, said third relay being responsive to inductive impulses repeated by said transformer relay, and a cir-

cuit for said motor magnet controlled by said third relay.

3. In an automatic telephone system, an incoming circuit a plurality of outgoing circuits, an automatic switch individual to said incoming circuit for connecting said incoming circuit to any of said outgoing circuits, an impulse transmitting device for transmitting impulses over said incoming circuit, an impulse relay normally connected to said incoming circuit and responsive to impulses transmitted from said impulse transmitting device, a transformer relay having a plurality of windings, a circuit for said transformer relay including one of its windings and arranged to be completed at said impulse relay, a third relay, a normally short-circuited circuit for said third relay including the winding thereof and another winding of said transformer relay, a motor magnet for operating said automatic switch, and a circuit for said magnet controlled at contacts of said third relay.

4. In an automatic telephone system, an incoming line, a plurality of outgoing lines, an automatic switch individual to said incoming line for extending said incoming line to any of said outgoing lines, a motor magnet for operating said automatic switch, an impulse relay normally connected to said incoming line, an impulse sender for transmitting impulses over said incoming line to directly operate said impulse relay, a transformer relay controlled by said impulse relay, normally short-circuited electro-magnetic means inductively connected to said transformer relay, change-over mechanism for determining the operation of said motor magnet, and a circuit for said motor magnet controlled at said change-over mechanism and said electro-magnetic means.

5. In an automatic telephone system, an incoming circuit, a plurality of outgoing circuits, an automatic switch for interconnecting said incoming circuit with any of said outgoing circuits, a primary motor magnet for operating said automatic switch in a primary direction, a secondary motor magnet for operating said automatic switch in a secondary direction, an impulse relay normally connected to said incoming circuit, said impulse relay being responsive to impulses transmitted over said incoming circuit, a second relay operating in synchronism with said impulse relay, electromagnetic means inductively connected to said second relay, change-over mechanism for terminating the operation of said primary motor magnet and for preparing an operating circuit for the secondary motor magnet and subsequently disabling said last mentioned operating circuit, an operating circuit for the primary motor magnet controlled by said change-over device and by said electromagnetic means, a test relay associated with said switch for pre-

venting said switch from seizing a wanted out-going circuit in the event that said circuit is busy and an operating circuit for the secondary motor magnet controlled by said test relay, by said change-over device and by 70 said electromagnetic means.

6. In an automatic telephone system, an incoming circuit, a plurality of outgoing circuits, an automatic switch for interconnecting said incoming circuit with any of 75 said outgoing circuits, a primary motor magnet for operating said automatic switch, an impulse relay normally connected to said incoming circuit, an impulse transmitting device for transmitting impulses over said incoming circuit to directly operate said impulse relay, a second relay under the control of said impulse relay, electromagnetic means inductively connected to said second relay and responsive to impulses repeated 80 thereby, a change-over device for determining the sequence of operation of said primary and secondary motor magnets, means for rendering interconnected circuits busy, a test relay for preventing the seizure of 85 a busy outgoing circuit by said automatic switch, a circuit for the primary motor magnet serially including said change-over device, said circuit being controlled at said electromagnetic means and a circuit for 90 said secondary magnet controlled by said testing means, by said change-over device and said electromagnetic means.

7. In an automatic telephone system, an incoming circuit, a plurality of outgoing circuits, an automatic switch for interconnecting said incoming circuit with any of said outgoing circuits, off normal contacts for said automatic switch, a primary motor magnet and a secondary motor magnet for operating said automatic switch, an impulse relay normally connected to said incoming circuit, an impulse transmitting device for transmitting impulses over said incoming circuit to directly operate said impulse 100 relay, a second relay operating under the control of said impulse relay, electromagnetic means inductively connected to said second relay and responsive to impulses repeated 105 thereby, a change-over device for determining the sequence of operation of said primary and secondary motor magnets, means for rendering interconnected circuits busy, a test relay for preventing the seizure of 110 a busy outgoing circuit by said automatic switch, a circuit for the primary motor magnet serially including said change-over device and said off normal contacts, said circuit being controlled at said electromagnetic means, and a circuit for said secondary 115 magnet controlled by said testing means, by said change-over device and by said electromagnetic means.

8. In an automatic telephone system, an incoming circuit, a plurality of outgoing cir- 120

cuits, an automatic switch for interconnecting said incoming circuit with any of said outgoing circuits, a primary motor magnet and a secondary motor magnet for operating said automatic switch, normally closed and normally open off-normal contacts for said automatic switch, an impulse relay normally connected to said incoming circuit, an impulse transmitting device for transmitting impulses over said incoming circuit to directly operate said impulse relay, a second relay operating under the control of said impulse relay and responsive to impulses repeated thereby, a change-over device for determining the sequence of operation of said primary and secondary motor magnets, means for rendering interconnected circuits busy, a test relay for preventing the seizure of a busy outgoing circuit by said automatic switch, a circuit for the primary motor magnet serially including said change-over device and said normally closed off-normal contacts, said circuit being controlled at said electromagnetic means, a substitute circuit for said primary motor magnet including said change-over device and said normally open off-normal contacts and a circuit for said secondary magnet controlled by said testing means, said change-over device and said electromagnetic means.

9. In an automatic telephone system, an incoming circuit, a plurality of outgoing circuits, an automatic switch for extending said incoming circuit to any of said outgoing circuits, a motor magnet for said automatic switch, an impulse relay normally connected to said incoming circuit, means for transmitting impulses over said incoming circuit to directly operate said impulse relay, a transformer relay responsive to the operation of said impulse relay, a third relay normally short-circuited by and inductively connected to said transformer relay, said third relay being responsive to impulses repeated by said transformer relay, an electromagnetic change-over device for determining the operation of said automatic switch, and a circuit for said motor magnet serially including said electromagnetic change-over device and being controlled by said third relay.

10. In an automatic telephone system, an incoming circuit, a plurality of outgoing circuits, an automatic switch for interconnecting said incoming circuit with any of said outgoing circuits, a motor magnet for advancing said automatic switch, an impulse relay normally connected to said incoming circuit, means for transmitting impulses over said incoming circuit for operating said impulse relay, a transformer relay controlled by said impulse relay, a third relay normally short-circuited by and inductively connected to said transformer relay

and responsive to impulses repeated by said transformer relay, said third relay being provided with normally open contacts, and a circuit for said motor magnet completed at said normally open contacts.

11. In an automatic telephone system, an incoming circuit, a plurality of outgoing circuits, an automatic switch for interconnecting said incoming circuit with any of said outgoing circuits, a motor magnet for advancing said automatic switch, an impulse relay normally connected to said incoming circuit, means for transmitting impulses over said incoming circuit to variably operate said impulse relay, a transformer relay controlled by said impulse relay, a third relay arranged to be controlled by impulses from said transformer relay, said third relay being provided with normally open contacts, a change-over device for controlling the operation of said motor magnet and a circuit for said motor magnet serially including said change-over device and said normally open contacts.

12. In an automatic telephone system, an incoming circuit, a plurality of outgoing circuits, an automatic switch for interconnecting said incoming circuit with any of said outgoing circuits, a motor magnet for advancing said automatic switch, a relay having primary and secondary windings in inductive relation, armature controlled contacts for said relay, means including said incoming circuit for transmitting impulses to the primary winding of said relay, a second relay, a circuit serially including the winding of said second relay and said secondary winding, means including said armature controlled contacts for short-circuiting the secondary winding of said first relay when said first relay is deenergized, and a circuit for said motor magnet controlled by said second relay.

13. In an automatic telephone system, an incoming circuit, a plurality of outgoing circuits, an automatic switch for extending said incoming circuit to any of said outgoing circuits, a motor magnet for advancing said automatic switch, an impulse relay normally connected to said incoming circuit, means for transmitting impulses over said incoming circuit to operate said impulse relay, a second relay controlled by said impulse relay to repeat two impulses for each impulse received by said last mentioned relay, means for short-circuiting certain of said repeated impulses and means for controlling said motor magnet in response to certain others of said repeated impulses.

In witness whereof, I hereunto subscribe my name this 14th day of January A. D. 1922.

WINFRED T. POWELL
